UNITED STATES PATENT OFFICE.

FLORYAN WAJDA, OF EAST HAMMOND, INDIANA, ASSIGNOR OF ONE-HALF TO
BARNEY J. GLINSKI, OF CHICAGO, ILLINOIS.

SWITCH-THROWING DEVICE.

1,110,088.

Specification of Letters Patent.

Patented Sept. 8, 1914.

Application filed November 27, 1912. Serial No. 733,839.

To all whom it may concern:

Be it known that I, FLORYAN WAJDA, a subject of the Emperor of Austria-Hungary, residing at East Hammond, in the county of Lake and State of Indiana, have invented certain new and useful Improvements in Switch-Throwing Devices, of which the following is a specification, reference being had therein to the accompanying drawing.

This invention relates to a switch throwing device, and the primary object of my invention is the provision of positive and reliable means, as hereinafter set forth, for manually and simultaneously operating a semaphore and switch stand and a switch mechanism.

A further object of this invention is to provide a switch throwing device that is simple in construction, durable, easy to install and highly efficient for the purposes for which it is intended.

With the above and other objects in view the invention resides in the novel construction, combination and arrangement of parts to be hereinafter specifically described and then claimed.

Reference will now be had to the drawing, wherein:

30 Figure 1 is a plan of a switch throwing device in accordance with this invention. Fig. 2 is a cross sectional view of the same, Fig. 3 is a side elevation of a portion of a switch stand, Fig. 4 is a cross sectional view taken on the line IV—IV of Fig. 2. Fig. 5 is a horizontal sectional view taken on the line V—V of Fig. 3 and Fig. 6 is a detail.

Further describing my invention in detail with reference to the accompanying drawing, wherein like numerals denote corresponding parts throughout: 1 denotes ties or other supports for the base flanges 2 of rails 3 and 4, said rails being held upon the ties by inner and outer rail fasteners 5 and 6. The rails 4 are provided with switch tongues 7 movable relatively to the rails 3 and said switch tongues are connected by a brace 8.

9 denotes bearings secured, as at 10 to the base flanges 2 of the rails 3, and journaled in said bearings is a shaft 11 that has collars 12 to prevent longitudinal displacement of said shaft. The shaft 11 has a spiral groove 13 and one end of the shaft has a pin wheel 14 which consists of a vertically disposed

disk having projecting from one face a circular row of lateral pins capable of meshing with the teeth of a horizontally disposed sector gear 28, the latter being carried by the shaft 25 to be hereinafter referred to. 60 The wheel 14 is more clearly shown in Fig. 6.

15 denotes T bars connected to the confronting sides of the switch tongues 7, adjacent to the ends thereof, said switch tongues being of the ordinary and well known type. Connected to the T-bars 15 by rivets 16 or other fastening means are parallel connecting bars 17 and 18 connected together by bolts 19 and nuts 20. The bars 17 and 18, adjacent to the ends thereof have U-shaped straps 21 extending under the shaft 11 and said straps are held by bolts 22 arranged transversely upon the bar 17.

23 denotes a depending pin, carried by the bar 18 that engages in the spiral groove 13 of the shaft 11 (see Fig. 4).

24 denotes a switch stand located at the side of the track and rotatably mounted in 80 said post is a vertical shaft or rotary member 25 that has the upper end thereof provided with a lantern 26 and semaphores 27. The lower end of the shaft 25 has a sector gear 28 that engages the pin wheel 14, said 85 wheel extending into an opening 29 provided therefor at the base of the stand 24.

30 denotes cranks carried by the shaft 25, above the post 24 and said cranks are connected by a handle 31. Movable mounted 90 in the cranks 30 is a latch 32 that is arranged in parallelism with the handle 31. The lower end of the latch 32 is adapted to engage in notches 33 provided therefor in the upper end of the post.

By gripping the handle 31 and the latch 32 said latch can be shifted out of one of the notches 33 and the shaft 25 rotated and the latch placed in engagement with the other notch. The shaft 25 is locked in either position. When movement is imparted to the shaft 25, the shaft 11 is revolved substantially a quarter revolution through the medium of the gear 28 and the pin wheel 14. With the pin 23 extending into the spiral 105 groove 13 the bearings 17 and 18 are shifted to simultaneously move the tongues 7 into or out of engagement with the rails 3, said tongues controlling the movement of rolling stock upon the rails 3 and 4.

110

It is thought that the operation and utility of the switch throwing device will be apparent without further description, and while in the drawings there is illustrated a preferred embodiment of the invention, it is to be understood that the structural elements are susceptible to such variations and modifications as fall within the scope of the appended claims.

10 What I claim is:—

1. In a switch throwing device the combination with rails and switch tongues, of bars connecting said switch tongues, a depending pin carried by one of said bars, a shaft revolvably supported beneath said rails and having a spiral groove to receive said pin, a pin wheel carried by one end of said shaft, a switch stand at the same end of said shaft, a rotary member rotatably mounted in said post, a sector gear carried by said rotary member and engaging said pin wheel for actuating the latter thereby rocking the shaft to shift the pin and move said tongues, and means carried by said rotary member for engaging said post and locking said rotary member in adjusted position.
- 15
- 20
- 25

2. In a switch throwing device, the combination with rails and switch tongues, of T bars carried by said switch tongues, bars connecting said T bars, a shaft rotatably mounted beneath said rails and having a spiral groove formed therein, a pin carried by one of said bars and extending in the groove of said shaft, a pin wheel carried by one end of said shaft, a switch stand at the same end of said rotary member, a rotary member rotatably mounted in said post, a sector gear carried by said shaft and engaging said pin wheel for actuating the latter thereby rocking the shaft to shift the pin to move said tongues, a handle supported from said rotary member to facilitate moving said rotary member, and a latch in connection with said handle for engaging said post and locking said rotary member in adjusted position.

In testimony whereof I affix my signature in the presence of two witnesses.

FLORYAN WAJDA.
